UNITED STATES PATENT OFFICE.

WILLIAM S. WRIGHT, OF SYRACUSE, NEW YORK.

DESIGN FOR A KITCHEN-CABINET.

SPECIFICATION forming part of Design No. 29,943, dated January 3, 1899.

Application filed November 23, 1898. Serial No. 697,290. Term of patent 7 years.

To all whom it may concern:

Be it known that I, WILLIAM S. WRIGHT, a citizen of the United States, and a resident of Syracuse, in the county of Onondaga and State of New York, have invented and produced a new and original Design for a Kitchen-Cabinet, of which the following is a specification, reference being had to the accompanying drawings, forming a part thereof.

Figure 1 shows a front elevation of the cabinet. Fig. 2 shows a side or edge view of the same. Fig. 3 shows a top or plan view.

The feature of the design resides in the form, shape, and arrangement of the cabinet, consisting of a cylindrical body 1, having rectangular side enlargements 2 2, and the cylinder having at its lower end an inverted

conical portion 3, with the small cylindrical portion 4, and having at its upper end a crowning-top 5, all as shown in the drawings.

Having described my invention, what I claim as new, and desire to secure by Letters Patent, is—

The design for a kitchen-cabinet, as herein shown and described.

In witness whereof I have hereunto set my hand, this 12th day of November, 1898, in the presence of two witnesses.

WILLIAM S. WRIGHT.

Witnesses:

J. S. BAKER,
J. H. HELMER.
